UNITED STATES PATENT OFFICE

SAMUEL J. ROBERTS, OF SCRANTON, PENNSYLVANIA, ASSIGNOR TO JOHN A. SCHADT,
OF SCRANTON, PENNSYLVANIA

SCHOOL DESK AND SEAT COVER

Application filed January 12, 1929. Serial No. 332,223.

This invention relates to improvements in school desks and seat covers and is particularly adapted for use in connection with the ordinary type of desk found in the lower 5 grades of public schools and the like.

A primary object of this invention is to provide a removable cover for a desk which will eliminate the possibilities for the pupil to mar or damage the desk or seat portions 10 by scraping or cutting with a knife or other sharp element or by defacing the surface with lead pencil marks.

A further object of this invention is to provide a desk and seat cover which may 15 be readily removed and replaced by a new portion or cover when the old section becomes damaged or soiled.

One of the principal objects of this invention is to provide a desk pad or cover held 20 in removable position by means of a front and side clamping member, which functions at the same time as a complete protection for the front and side edges of the desk or seat portions.

25 Other objects of this invention will appear from the following detailed description of the device and as disclosed in the two sheets of drawings which are herewith made a part of this application.

30 In the drawings—

Figure 1 illustrates a perspective view of the desk and seat cover according to this invention in removable relationship with the ordinary desk found in public schools.

35 Figure 2 illustrates a vertical sectional view of the desk, seat and back portions to an enlarged scale disclosing the means for binding and interlocking the desk, seat and back cover portions together.

40 Figure 3 represents a rear elevational view of the lower portion of the seat back disclosing the means for holding the free ends of the seat back binding strips in interlocked relationship with the edge binding strips of 45 the seat portion.

Figure 4 illustrates a perspective view of the interlocking ends of the binding strips for the seat back and seat portions, just before being brought into interlocked position.

50 Figure 5 is a top sectional plan view of the

rear portion of the top of the desk and the seat back, taken along line 5—5 of Figure 2, showing particularly the means by which the side binding strip of the desk top is interlocked with the binding strip of the seat back. 55

Figure 6 illustrates a perspective view of a portion of the binding strip for the seat back disclosing the tongue or interlocking tab elements extending therefrom. 60

Figure 7 illustrates a sectional view to an enlarged scale disclosing the means for securely clamping or interlocking the desk binding strip in operative position for holding the cover in place. 65

Figure 8 represents a sectional view of Figure 7 taken along line 8—8. 65

Figure 9 illustrates a top plan view of the desk cover with a portion broken away showing the relative position of the desk 70 pad or cover and the binding strips.

Figure 10 represents one modification of a means for holding the desk binding strip in fixed position on the desk, as taken along line 10—10 of Figure 9. 75

Figure 11 represents a sectional view of Figure 10 taken along line 11—11.

Figure 12 illustrates a bottom plan view of Figure 11.

Figure 13 represents a perspective view of the desk pad or cover and the front and side edge binding strip thereof. 80

Figure 14 illustrates a perspective view showing the rear bottom portion of the desk and disclosing the notch plates for receiving the tongue portions extending from the desk binding strip. 85

Numeral 1 designates the desk portion, while numerals 2 and 3 designate the back and seat sections of a desk commonly found in the graded public schools, which under usual conditions are subjected to the hardest kind of usage including the excessive damage due to disfiguring by means of knives, pencils and the like of pupils. 90

In order to prolong the life of school furniture this invention provides a removable desk pad or cover 4, back seat cover 5, and seat cover 6, the cover portions being held in firm and fixed relationship to the desk by 100

means of binding strips or clamping members 7, 8 and 9.

The removable covers may be made of any suitable material such as metal, cloth, paper or pad material of the usual type, while the binding or clamping strips should be made of a material having sufficient clamping power for the purpose desired. The most suitable material for the binding strips should be metal in order that interlocking tongue portions 10, 11, 12, 13, 14, and 15 may be integrally formed therefrom.

The desk cover 4 is formed having a notched section 16 extending around three side edges for receiving the binding strip 7, which is preferably channel-shaped and of sufficient width to include within the channel the desk cover 4 and the desk top 1, as clearly shown in Figure 8.

When the desk cover 4 has been damaged, it may be easily replaced by a new cover, the binding strip 7 being detachably positioned in relationship to the desk top and cover. As one means for holding the binding strip

7 in fixed relationship to the cover 4 and desk 1, it is preferred that suitable openings 17 be formed in the lower flange 18 of the binding strip 7, as clearly disclosed in Figures 7 and 8, in order to cooperate with a spring catch element 19 adapted to be fastened to the underside of the desk 1 by means of screws 20, or otherwise, in such a manner that a portion of the catch element 19 will extend through the openings 17 when the binding strip 7 is located in position, thereby holding the desk 1, cover 4, and binding strip 7 in fixed and firm relationship to each other until it is desired to replace the cover 4 with a new one.

The removable cover 5 is held in fixed position in relationship to the seat back portion 2 by means of the binding strip 8 having rearwardly extending tab portions 10, which function to cooperate with upwardly extending tab portions 11 from the binding strip 7, at the rear upper portion of the seat back.

The seat cover 6 is held in fixed relationship to the seat 3 by means of binding strip 9, which is held in interlocked relationship with the free ends of the binding strip 8 by means of tongue portions 13, 14, and 15, which are adapted to extend through cooperating slots 21 and 22 of the binding strip 8. From the construction of the binding strips it is apparent that they may be easily removed and the cover portions released as desired.

As a further modification of means for holding the binding strip 7 in fixed relationship to the cover 4 and desk 1, a tongue or latch portion 23 may be integrally formed from the lower flange 18 of the binding strip 7, as clearly disclosed in Figures 11 and 12, in such a manner that when the binding strip

7 is located in position, the latch 23 will function to be received within an opening 24 of a plate 25, which is securely fastened to the desk 1 by means of screw 26 or otherwise.

This invention provides a very efficient cover for school desks, simple and inexpensive of manufacture and easily applied to suitable furniture in the school room.

It will be noted that by first applying the clamping member 7 to the desk part and sliding the clamping member 8 down over the back part and then sliding clamping member 9 in over the seat part, the interlocking of tongues 13, 14 of member 9, with tongues 21, 22 of member 8 will interlock both of said members 8 and 9 into fixed relation with the seat and back respectively, while the engagement of tongues 10 of member 8 with tongues 11 of member 7 will prevent the withdrawal of the clamping member 7 even without the use of the additional or supplementary locking members 17 or 24 provided for more securely holding member 7 to the desk top if desired.

It will be understood that many changes and modifications may be made in the form of embodiment of this invention within the scope of the following claims without departing from the spirit thereof.

What I claim is:

1. A removable cover for a school desk part, a U-shaped clamping member of channel cross section adapted to hold the cover and desk part in fixed relationship to each other, notches in the cover for slidably receiving the clamping strip, cooperating interlocking means between the desk part and the clamping member for holding the desk, cover, and clamping member in detachable relationship.

2. In a school desk having desk top, seat, and back rest sections, detachable cover portions for the sections, clamping members slidably positioned along three edges of each of the sections for detachably holding the covers in position and means for interlocking said clamping members.

3. In a school desk having desk top, seat, and back rest sections, detachable cover portions for the sections, U-shaped clamping members slidably positioned along three edges of each of the sections for detachably holding the covers in position, three edges of each of the covers being notched to slidably receive the clamping members, tongue portions extending from the ends of the clamping members, the adjacent tongues of said clamping members adapted to cooperate to hold the clamping members and cover sections in fixed relationship to the desk top, back rest, and seat.

4. In a combination desk and chair having desk, back and seat parts, covers for the desk, back and seat and means for removably se-

curing said covers in position comprising three substantially U shaped rim engaging clamping members of channel cross-section adapted each to engage and secure together 5 three edges of the desk, back and seat parts with their superimposed covers, said clamping members having interlocking engagement members.

5. In a combination desk and chair having 10 desk, back and seat parts, and removable covers for said parts, U shaped clamping members of channel cross section to engage the marginal edges of said parts and their covers, tongues on the ends of each of said 15 clamping members and tongues on the flange of the leg parts of one clamping member whereby adjacent parts of said members, when assembled interlock to form a unitary clamping member.

20 6. The structure specified in claim 5 in which the interlocking tongues on the clamping members constitute mortise and tenon connections to prevent the spreading of the leg members or the longitudinal withdrawal 25 of the legs of one clamping member from engagement with another.

In testimony whereof I affix my signature
SAMUEL J. ROBERTS.
